UNITED STATES PATENT OFFICE

ARMAND DELAHAYE, OF CALAIS, FRANCE

DESIGN FOR LACE

Application filed May 27, 1931. Serial No. 39,999. Term of patent 3½ years.

To all whom it may concern:

Be it known that I, ARMAND DELAHAYE, a citizen of France, and a resident of Calais, France, have invented a new, original, and ornamental Design for Lace of which the following is a specification, reference being had to the accompanying drawing, forming part thereof.

The figure is a plan view of a piece of lace, showing my new design.

I claim:

The ornamental design for lace, as shown.

ARMAND DELAHAYE.
